CLOSURE

Howard J. Findley, Chardon, Ohio, assignor to
Eaton Manufacturing Company, Cleveland,
Ohio, a corporation of Ohio

Application January 21, 1946, Serial No. 642,467

6 Claims. (Cl. 220—44)

1

This invention relates to closures and more particularly to pressure and vacuum relief closures.

Broadly the invention comprehends the provision of caps or closures for fluid containers or closed fluid systems, said closures having valve means therein providing for the automatic relief of pressure and vacuum from the containers or systems with which they are adapted to be associated.

Although numerous closures for automatically regulating subnormal and abnormal pressures above and below predetermined requirements in radiators, gas tanks, and other fluid containers subject to variations in fluid pressure within the fluid containers have been devised, manufactured, and used, none has achieved the safety and structural limitations such that the pressure within the tanks can be kept within a confined predetermined range depending upon the physical properties of the fluid containers and possible variations in pressure range of the fluid contents thereof. Accordingly the instant invention through the employment of a snap action diaphragm two way valve arrangement wherein the diaphragm is initially adjustable to desired snap action pressure depending on the application of the closure, the closure can be made and adjusted within required predetermined range of operation thereof.

An object of the invention is the provision of a closure for fluid containers having a combined pressure and vacuum relief valve incorporated therein.

Another object of the invention is the provision of a closure for fluid containers for regulating the relief of pressure and vacuum from the containers within specific predetermined limits.

A further object of the invention is the provision of a snap action diaphragm valve closure for fluid containers for the relief of vacuum and pressure therefrom.

A still further object of the invention is the provision of a closure for fluid containers having a single two way pressure and vacuum relief valve embodied therein, said valve being initially adjustable to specific operation conditions required.

And yet a further object of the invention is

2

the provision of a closure for fluid containers for automatically regulating the subnormal and abnormal pressures in fluid containers of simple construction and effective, efficient operation within prescribed pressure operating range.

Other objects and advantages of the invention will appear from the following description taken in connection with the drawings, forming a part of the specification; and in which:

10 Fig. 1 is a fragmentary top plan view of the cap or closure constituting the invention.

Fig. 2 is a vertical cross sectional view of the closure illustrating the snap action diaphragm two way valve incorporated in the closure, and

15 Fig. 3 is an enlarged fragmentary vertical cross sectional view of the two way valve arrangement.

In the widespread adoption of closed systems for fuel tanks, cooling systems, and the like, it is

20 essentially important that closure means be provided that are capable of effectively, automatically regulating the subnormal and abnormal pressures therein within prescribed limits, while at the same time preventing loss of fluid contents thereof through boiling, as in the case of cooling systems, or through vaporization in the case of vehicle fuel tanks. In closures of this nature it is of vital importance that the valve means incorporated therein be quickly, effectively responsive

25 to pressure and vacuum changes in the associated closed fluid systems within a controlled predetermined operating range such that the valve is positively responsive to the proper limits of pressure and vacuum in the systems, thus

30 preventing any possible collapse or explosion of the system due to undesirable subnormal or abnormal atmospheric pressures being created in the system.

The instant invention resides in the provision

40 of a closure for closed fluid systems having valve means incorporated therein for the relief of pressure and vacuum from said systems quickly and effectively, said valve means assuring of quick

45 snap action diaphragm that is movable between two limits, and which diaphragm is adjustable initially to its proper operating resiliency so as to effectively control the limits of pressure and vacuum at which the valve mechanism should operate. The diaphragm is associated with and

adjustable to its proper operating resiliency by a central valve member that is movable relative to the diaphragm to permit of the escape of pressure from the system with which the closure is associated or entrance of pressure to the system thereof upon creation of a vacuum in the system thus providing for regulation of the system to function between certain limits of vacuum and pressure such, for example, as from $\frac{1}{2}$ lb. sub-atmosphere to $1\frac{1}{2}$ lbs. superatmosphere.

Referring to the drawings for more specific details of the invention 10 represents generally a cap or closure adapted to be used on closed fluid containers or systems.

The cap 10 comprises an outer circular closure member 12 having a depending annular skirt 14, said skirt in turn being provided with a pair of external radial protrusions 16 and a pair of inward radially disposed lugs or fingers 18, the protrusions providing means for manually tightening or removing the cap from assembly with its associated system, not shown, and fingers 18 are adapted to associate with proper connections on the system to thus clamp the closure in installed position.

The cover 12 has affixed centrally thereof a hub 20 comprising a body 22 and an end 24 peened over to hold an annular ring 26. The hub 20 has a centrally threaded bore 28 adapted to receive an adjusting screw 30 in threaded relation thereto, the purpose of which will herein-after appear. The screw 30 has a central aperture 32 provided in one end and a screw driver slot 34 in the opposite end thereof.

A flexible dished ring 36 is mounted upon hub 20 with a sealing washer or spacer 38 mounted on the hub interposed between the cover 12 and ring 36. A cup shaped member 39 mounted concentrically on the hub 20 juxtaposed the ring 36 is provided with an annular grooved flange 40, the purpose of which will herein-after appear, and a plurality of circumferentially spaced ports 42 in its body.

The grooved flange 40 has fitted therein in closely packed relation a thin metallic snap action diaphragm 44, an annular rubber washer 46, a disc member 48, and an annular rubber sealing ring 50, said disc having a perforated dished portion 52 and radial split portions providing fingers 54 and 56 embracing ring 50 so as to hold it in snug sealing engagement in the member 39.

The diaphragm 44, as shown by Fig. 2 as assuming a normally flat position is provided with a sealing and strengthening rib 58, a plurality of circumferentially spaced ports 60 and a central opening 62 for receipt of a valve post 64 adapted for reciprocation therein. The valve post 64 is cylindrical in shape and comprises a central body portion 66, a radial flange 68, an axial extension 70, the end of which is adapted to abut the bottom of aperture 32 in screw 30, and a reduced portion 72. At the opposite extremity thereof is mounted a concentric ring 74, an annular sealing member 76 and a disc 78 having an upturned annular flange 80 embracing the ring 74, the ring 74, member 76 and disc 78 being screwed upon the reduced portion 72 of the post 64 by a peened-over flange 82 constituting a part of post 64. The post 64 is normally mounted in fixed relation to the diaphragm by the inner positioning of a light coil spring 84 between the flange 68 and diaphragm 44, said spring normally holding the sealing member 76 in sealing engagement upon rib 58 of diaphragm 44.

The closure 10 is adapted to fit upon a filler

neck 86 of an appropriate fuel tank, cooling system or any other suitable closed fluid system comprising a body portion 88, an annular flange 90 and a reduced axial flange 92, flange 90 being inserted between fingers 18 and ring 36 and resiliently held therebetween such that a rib 94 on enclosure 86 at the junction of body 88 and flange 92 is held in sealing engagement upon the sealing ring 50. The filler neck 86 is provided with an opening 96 in the wall of body portion 88 providing communication of the valve mechanism of the closure and the atmosphere.

In the assembly of the component parts of the closure prior to installation in operational use with closed fluid systems it is of utmost importance that the diaphragm 44 be initially set to its proper operating flexibility by the threading of screw 30 to a position such that the diaphragm will be responsive to the proper pressure desired for the operation thereof. After the setting of the screw to desired position it is then fixedly screwed in place as indicated at 98 by soldering inasmuch as no further adjusting is necessary in addition to the initial setting thereof. It is to be realized that the adjustment of the diaphragm to a predetermined resiliency is a vital feature of the structure in that because of the inaccuracies that occur in the manufacture of diaphragms for snap action pressure operations it is almost impossible to produce a number of like diaphragms that vary minutely in snap action pressure response and is thereby necessary, as in this case, that they be adjusted to operating requirements prior to the use thereof. With the installation of the closure 10 in the filler neck 86 of an engine cooling system, gas tank, or other fluid container, or system, the valve mechanism of the closure is operable to relieve pressure or vacuum formation in the system above and below predetermined requirements. Upon the generation of pressure in the system the pressure on the fluid is transmitted through ports and acts across the face area of diaphragm 44, said diaphragm resisting pressure creation to the extent of its setting which for illustration might be $1\frac{1}{2}$ lbs., wherein upon the attainment of such pressure acting on the diaphragm the diaphragm is moved or snapped from its normal valve seated position to the position indicated by dotted line 100 thereby providing for relief of pressure past the valve through ports 60 into a chamber 102 formed between the diaphragm and member 38 through ports 42 and thence through opening 96 to the atmosphere. It is to be noted that in the movement of the diaphragm to dotted line position 100 that the diaphragm acts against the load of the coil spring 84 set to predetermined load position by adjustment of the screw 30 abutting the valve posts and thus inhibits movement of the valve post in one direction. In the case of the creation of a vacuum in the system below a desirable allowable amount, say $\frac{1}{2}$ lb. a suction or vacuum action acts upon the valve mechanism 74-76-78 affixed to the valve post 64 to overcome the load of spring 84 thus moving the valve from its seat permitting the passage of atmospheric pressure from without the closure in a reverse direction from the passage of pressure from the system. Normally wherein the pressure and vacuum in the system remain within the limits of the illustration used, that is, $1\frac{1}{2}$ lbs. pressure and $\frac{1}{2}$ lb. vacuum the system will remain closed thereby preventing vaporization of the gas from fluid tanks, loss of cooling medium from cooling systems, etc., in keeping with the

mode of application of the closure. This description completes all phases of operation of the closure for its intended function.

While this invention has been described in connection with certain specific embodiments, the principle involved is susceptible of numerous other applications that will readily occur to persons skilled in the art. The invention, therefore, is limited only as indicated by the scope of the appended claims.

What I claim is:

1. In a closure for closed fluid systems, a hollow cap body having a central hub affixed thereto, a concentric flexible disc mounted on the hub, a cup-shaped member concentrically mounted on the hub in axial abutting relation to the disc, a two-way valve mechanism supported concentrically on the cup member at the lip end thereof comprising a resilient thin snap action flexible metallic diaphragm and a spring pressed central valve member, and means threaded in the hub for adjusting the pressure responsive load of the diaphragm through the medium of the valve member.

2. A closure device for fluid containers comprising a hollow cylindrical body having a central hub, a flexible dished member mounted on the hub, a cup-shaped member mounted on the hub with the dished member interposed between it and the cylindrical body, a valve mechanism mounted on the cup-shaped member at the free end thereof comprising a flexible snap action diaphragm having a central aperture and a plurality of circumferentially spaced ports and a spring pressed axially movable cylindrical sealing member having a part mounted for reciprocation in the aperture and a part cooperating with the diaphragm for controlling the ports in the diaphragm, and means threaded in the hub for setting the diaphragm to required load responsiveness.

3. A closure for cooperation with the filler neck of a closed fluid system comprising a hollow, shallow cylindrical body having a central hub integral therewith, a valve supporting member mounted concentrically on the hub having ports in the body thereof, a flexible disc member mounted on the hub interposed between the body and valve supporting member adapted for tension holding relation with the filler neck when the closure is assembled thereon, a valve mechanism secured in the valve supporting member at one end thereof comprising a thin flexible snap action diaphragm having a central aperture, a plurality of equi-spaced circumferential ports, and a subtended annular sealing rib and a cylindrical valve member reciprocably mounted in the aperture and spring supported on the diaphragm having an annular sealing element adapted to cooperate with the sealing rib on the diaphragm effective to control the ports in the diaphragm, and means for moving the cylindrical valve member relative to the cylindrical body and against the resistance of the spring to set the diaphragm to the proper pressure operating load desired.

4. A closure for closed fluid systems comprising a shallow hollow cylindrical cap member, a flexible disc mounted centrally of the cap cooperative therewith for resiliently holding the closure in position when assembled for use on a closed fluid system, a cup-shaped member mounted upon the cap in abutting relation to the disc having a plurality of circumferential openings in the wall thereof, a valve assembly supported on the cup-shaped member at the open

end thereof and forming a chamber therebetween with the cup-shaped member, comprising a two position snap action diaphragm having a plurality of circumferential ports therethrough continuously open to the chamber, a sealing member arranged on the diaphragm and normally, resiliently held thereon closing the ports from communication to the side of the diaphragm oppositely disposed from the chamber, and an annular sealing ring supported on the lip of the cup-shaped member adapted for sealing engagement with the fluid system, when the closure is assembled thereon, said diaphragm movable to a position for opening the chamber to communication with the fluid system upon the attainment of a predetermined pressure in the system.

5. A closure device for cooperation with the filler neck of a closed fluid system comprising a cylindrical cap member, a flexible curved disc member supported centrally thereof concentrically upon the cap, a cup-shaped member mounted in concentric axial abutting relation to the disc, a valve mechanism supported on the cup-shaped member at one end thereof including a snap action metallic diaphragm having an annular rib and a plurality of circumferential openings within the confines of the rib, and a valve member normally, resiliently held upon the diaphragm in sealing engagement with the annular rib of the diaphragm, an annular resilient sealing member supported on the lip of the cup, and means arranged centrally of the cap, disc and cup-shaped member for predeterminedly adjusting the pressure at which the diaphragm is adapted to be responsive for movement from valve closed to valve open position, said cap, flexible disc and annular seal all cooperating with the filler neck of a closed fluid system upon assembly of the closure thereupon to retain the closure thereon and seal the fluid system from the atmosphere and said diaphragm being adapted to snap action movement when a predetermined pressure is attained in the fluid system.

45. 6. A closure for cooperation with a filler neck of a closed fluid system having spaced outer and inner seats and an atmosphere connection therebetween comprising a cap body adapted for releasable connection with the neck, a flexible disc

50 in the cap body for cooperation with the outer seat of the filler neck, an axial depending cup-shaped member mounted on the cap having a sealing lip which is adapted to be engageable with the inner seat of the filler neck when the closure is applied to the neck, a valve mechanism supported on the cup-shaped member providing a chamber therebetween with the cup-shaped member including a thin snap action diaphragm having a plurality of circumferential openings

55 therethrough and an annular depending rib, a spring pressed sealing means supported on the diaphragm having normal sealing engagement with the rib whereby the openings in the diaphragm are normally sealed from communication with the fluid system to which the closure is adapted while at the same time being continuously open to the chamber, said cup-shaped member having a plurality of openings in the wall thereof providing communication of the

60 chamber with the atmosphere through the atmospheric connection in the neck, and an adjustment means secured in the cap for engagement with the sealing means for establishing the predetermined pressure at which it is desired to 70 permit snap action of the diaphragm relative to

the sealing means for the release of pressure from the closed fluid system.
